UNITED STATES PATENT OFFICE.

SAMUEL ARTHUR NICHOLS, OF LOS ANGELES, CALIFORNIA.

EXTENSION-TABLE.

No. 881,610.

Specification of Letters Patent. Patented March 10, 1908.

Application filed July 23, 1906. Serial No. 327,451.

To all whom it may concern:

Be it known that I, SAMUEL ARTHUR NICHOLS, a citizen of the United States, residing at Los Angeles, in the county of Los Angeles and State of California, have invented new and useful Improvements in Extension-Tables, of which the following is a specification.

My invention relates to that class of extension tables in which temporary leaves forming a part thereof are secured thereto, and an object thereof is to provide a table which can be immediately converted into a table of larger size.

Another object is to provide a table in which the extension means carried thereby are hidden from view when the table is in its normal condition.

A further object is to provide a table that is simple and effective in operation, durable and economical in construction and which will answer the purpose of two distinct kinds of tables.

I accomplish these objects by the device described herein and illustrated in the accompanying drawings, in which:

Figure 1.—is a perspective view of my table in its folded position. Fig. 2.—is a transverse section of my table in its extended position. Fig. 3.—is a perspective view of the table with the divided top in its opened or extended position. Fig. 4.—is an enlarged transverse section of the table in its folded position. Fig. 5.—is a detail perspective view of one of the anchor means for the divided top.

The table preferably consists of a frame 10 having legs 11 and a shelf 12. Attached to the frame is a top 13 divided into two rectangular sections 14 and 15, each section having an extension arm 16 rigidly secured thereto on the under side thereof. These arms are pivotally attached to the side rails 17 of the frame, so that when it is desired to enlarge the table the sections 14 and 15 can be swung apart to occupy positions parallel to each other (as shown in Fig. 3). The side rails 17 of the frame are set slightly below the frame 10 so that when the top is swung apart the upper edges 19 of the frame 10 will form a stop for the extension arms 16 to limit the further movement of the sections 14 and 15.

Secured to the inner edges of the sections 14 and 15 are headed pins 32 which are adapted when the divided top is swung apart to engage slotted brackets 33 which are se-

cured to the inside faces of the end rails of the frame 10. These anchors prevent any vertical movement of the sections when in their extended positions. On the inner edges of each section 14 and 15 are tongues 20 which are adapted to engage recesses 22 formed on the under face of the inner edge of the sections 14 and 15 and support the foldable leaves when the table is in its extended or open position.

The under faces of the foldable leaves are provided with recesses 21 which register with tongues 20 when the foldable leaves are in their extended position. A pivoted catch 23 having a handle 23' attached to one of the rails 17 engages a notched recess 24 when the divided top is in its closed position, thereby locking it from accidental displacement.

Pivoted below the divided top 75 is a pivoted leaf 25 and a foldable pivoted leaf 26, adapted to fill the opening created by the movement of the divided top. Leaf 25 is pivotally attached to one of the rails 17 by means of a sliding pivot 27, the purpose of 80 this sliding pivot is to provide room for the withdrawal of leaf 26. After the leaf 25 has been withdrawn leaf 26 is withdrawn and leaf 25 is then pushed toward leaf 26 until the pins 27' enter the sockets 28 on the inner 85 edge of the leaf 25, thus forming with leaf 26 a perfect joint, the pins 27' securing it from vertical movement. Leaf 26 is preferably composed of two sections, a pivoted section 29 and a hinged section 30. Section 29 has 90 on each end an extension arm 31, which is pivoted to the inside of the end of the frame at one side of the center thereof so as to provide room for its withdrawal.

Secured to one of the rails 17 is a downwardly extending arm 34, the outer end of which is bent inwardly at right angles thereto and forms a combined rest and stop 34' for the foldable pivoted leaf 26, the hinged section 30 contacting with the rest and being 100 supported thereby and the outer end of the pivoted section bearing against it. It will thus be observed that the combined weight of sections 29 and 30, to the left of pivoted bar 31, is greater than the weight of section 105 29 to the right, when the leaves are in the position shown in Fig. 4. The outer end of section 29 will therefore be forced upwardly against stop 34', while the outer end of section 30 is supported by the same stop.

The operation of the table is as follows:— When it is desired to extend the table, the

divided top is drawn apart until the sections 14 and 15 reach the limit of their movement. Leaf 25 is then withdrawn from the opening to its extended position, and hinged portion 5 30 of leaf 26 is then pulled upwardly and outwardly, thus causing the pivoted section 29 to revolve on its pivot until the leaf has reached its extended position, the pivoted section 29 occupying the central position of 10 the extended top. Leaf 25 is then pushed toward section 29 (the sliding pivot permitting) until the pins 27' enter the sockets 28 of the leaf 25.

It will be observed from the foregoing description that I have produced a novel and useful extension table in which the extension leaves are attached thereto, thus doing away with the necessity of storing the leaves in places that at times are inaccessible, and at 15 20 the same time have provided a table that can be used as an ordinary drawing room or library table when not in use as a dining table.

Having described my invention, what I 25 claim as new and desire to secure by Letters Patent is:—

1. A device of the class described, com-

prising a frame having end leaves movably attached thereto; a centrally disposed foldable side leaf pivotally attached to one of 30 the side rails of said frame; and a centrally disposed foldable leaf comprising two sections hinged together, pivotally attached to the end rails of said frame, said foldable leaves adapted to fill the opening created by 35 the movement of the end leaves.

2. A device of the class described, comprising a frame having end leaves movably attached thereto; a centrally disposed foldable side leaf slidingly pivoted to one of the 40 side rails of said frame; and a centrally disposed foldable leaf comprising two sections hinged together, pivotally attached to the end rails of said frame, said foldable leaves adapted to fill the opening created by the 45 movement of the end leaves.

In witness that I claim the foregoing I have hereunto subscribed my name this 16 day of July, 1906.

SAMUEL ARTHUR NICHOLS.
